ABSTRACT

A revolver has a cylinder, including a by-pass ratchet, mounted for rotation within a frame. A trigger is pivotally mounted in the lower portion of the frame. A cylinder lock is positioned in the lower portion of the frame adjacent the frame and is so arranged that it locks the cylinder in certain trigger positions. A hammer is mounted for rotation in the rear portion of the frame and is urged into the firing position by means of a compression spring. The lower portion of the hammer is adapted to contact the trigger and move it to a rearward position during movement of the hammer from the firing position to the cocked position. A by-pass hand and a safety connector are pivotally mounted on the trigger on separate pivots. A leaf spring is interposed between the safety connector and the hand to urge the hand in the direction of the cylinder. The pin upon which the hand is mounted is significantly smaller than the mounting aperture on the hand. As the hammer is cocked the hand engages the by-pass ratchet to rotate the cylinder to a locked position. The trigger pull in the cocked position is substantially constant at all cylinder positions since the effects of the friction between the hand and the ratchet are not transmitted to the trigger because of the play in the connection between the trigger and the hand.

BY-PASS HAND CONNECTION

BACKGROUND OF THE INVENTION

This invention relates to revolvers and more particularly to revolvers which utilize a hand to rotate the cylinder thereof.

Revolvers incorporating cylinders having ratchets which are rotated by a by-pass hand are well known in the prior art. Typically, these prior art revolvers incorporate a pin on the trigger or the hand which serves to mount the hand, which, in turn, is arranged to engage and drive the ratchet during rearward movement of the trigger. When the trigger is pulled or the hammer is cocked, the extremity of the by-pass hand engages the ratchet and turns the cylinder, cause

In order for a revolver incorporating a by-pass hand to be properly timed, the cylinder must lock during rearward movement of the hammer to a cocked position and the hand must then be able to slide by the ratchet during the last few degrees of hammer rotation. This arrangement necessitates that the ratchet teeth be formed to exacting specifications. Since it is virtually impossible to manufacture six perfectly formed ratchet teeth, revolvers of the aforementioned type will have a slightly different trigger pull on one or more chambers due to the friction occasioned between the extremity of the hand and the ratchet when the trigger is squeezed to fire the revolver. Also, any residue which adheres to the ratchet will not only case the cylinder to revolve with noticeable drag, but will also result in more friction between the extremity of the hand and the ratchet than would otherwise be encountered.

While a revolver which requires varying trigger pulls in the respective positions of the cylinder may not be found objectionable in certain applications, this characteristic will militate against the accurate operation of the revolver. For example, if the revolver is used primarily for target shooting, a varying trigger pull would clearly be undesirable.

SUMMARY OF THE INVENTION

The invention provides a means by which a revolver of the aforementioned type can respond to a consistent trigger pull on every chamber. The invention achieves this result by loosely mounting the hand upon the trigger by means of a pin structure which interconnects the hand and trigger. The structure is received in a hole which is significantly larger than the structure. Thus, when the trigger is pulled to disengage the sear on the trigger from the notch on the hammer, the trigger pull will not have to be sufficient to overcome the friction between the extremity of the hand and ratchet since the motion of the trigger is not transmitted to the hand along its axial direction.

The invention, in addition to achieving a consistent trigger pull in the various cylinder positions, yields an improved trigger return due to the fact that the trigger spring will jerk the hand because of the momentum developed by the trigger before the pin structure contacts the periphery of the hole. Another advantage, inherent in the instant invention, is that the hand may float with respect to the trigger, thereby compensating for any surface irregularities which may be present in the frame, side plate, trigger or ratchet. This arrangement not only contributes to an improved trigger return, but also allows for greater tolerances in the manufacture of the above enumerated components.

Accordingly, it is a primary object of the invention to provide a revolver which yields a consistent single action trigger pull on every chamber.

It is another object to provide a means which contributes to an improved trigger return.

A further object is to provide a revolver having a consistent single action trigger pull on every chamber in which the manufacturing tolerances of some of the components of the revolver may be greater than those which would ordinarily be required.

These and other objects will become more readily apparent from the following detailed description taken in connection with the accompanying drawings.

BRIEF DESCRIPTION OF THE DRAWINGS

FIG. 1 is a side view, partly broken away and partly in section, showing a handgun incorporating an embodiment of this invention with its hammer in the neutral or fired position;

FIG. 2 is a partial side view showing details of the handgun firing mechanism with its hammer in the cocked position;

FIG. 3 is a section view taken generally along line 3—3 of FIG. 1;

FIG. 4 is an isometric view, on a reduced scale, showing a portion of a connector in relation to an inside wall of a sideplate of the handgun frame;

FIG. 5 is an enlarged side view showing the connector and hand in relation to the sideplate when the hammer is in the cocked position;

FIG. 6 is a partly broken away view of the trigger and the hammer showing the engagement of the respective sears;

FIG. 7 is an enlarged view, partly broken away, showing the mounting arrangement between the hand and the trigger;

FIG. 8 is a perspective view of a hand according to another embodiment of the invention.

DETAILED DESCRIPTION OF PREFERRED EMBODIMENTS

Referring now to the drawings in detail, a preferred embodiment of this invention is shown in a revolver-type handgun 10 having a barrel 12 secured to a frame 14. Pivoted mounted in the frame 14 is a swing-out cylinder 16 suitably chambered for receiving cartridges (not shown) to be fired in sequence by a firing mechanism 18.

To load and unload the cylinder 16, a cylinder bearing pin 20 is retracted against a spring bias coaxially away from rotary bearing engagement with the cylinder 16 to permit it to be bodily displaced angularly about a pivotal axis X—X of a crane 22. The pivotal axis X—X of the crane 22 is in parallel spaced relation to the central rotational axis of the cylinder 16 which is coincident with a spring biased ejector rod 24. By such construction, both the crane 22 and cylinder 16 may be swung outwardly as a unit from a closed position within the frame 14 (shown in the drawings) to an open position.

In the open position, spent cartridge casings (not shown) may be unloaded by depressing the ejector rod 24 to move a by-pass ratchet ejector 26 rearwardly to unseat the cartridge casings. Upon releasing the ejector rod 24, the ratchet ejector 26 again seats against the cylinder 16, which may then be loaded with fresh cartridges before being closed.

Upon being seated in the closed position, the spring biased bearing pin 20 automatically moves forwardly into bearing engagement with the cylinder 16 to support it for rotary movement, and each cylinder chamber (not shown) is individually maintained in coaxial alignment with the barrel 12 by an end of a bolt 28 which seats within one of a series of cylinder locking cuts, such as at 30, which, in turn, correspond in number to the cylinder chambers. The bolt 28 pivots about a pin 32 fixed to the frame 14, and a torsion spring 34 continuously urges the bolt 28 toward seating engagement within a cylinder locking cut 30.

To ensure low cost manufacture while also minimizing close tolerance requirements, the frame 14 is formed with a cavity 36 having a flat internal floor 38 for receiving the firing mechanism components which by virtue of the flat floor construction are quickly and easily assembled and replaced as the need arises.

For firing the cartridges, the firing mechanism 18 is provided a trigger device 40 and a by-pass hand device 42 pivotally supported thereon by means of a pin structure 42a which is received in an aperture 42b. The hand serves to advance the ratchet ejector 26 a selected angular distance to index each chamber, in turn, into alignment with the barrel 12 to be sequentially fired by dropping a hammer 44 to actuate a firing pin 46.

The hammer 44 is supported on the frame 14 by a pivot pin 48 and is released from a cocked position (FIG. 2) to move toward a neutral or fired position (FIG. 1) by the movement of the trigger 40. The hammer 44 returns to the fired position under the force of a main spring 50. The latter is coiled about a guide rod 52 extending through an apertured thrust plate 54 in the frame 14 with the main spring 50 bottomed on the thrust plate 54 and urging an upper ball end 56 of the guide rod 52 into a socket 58 for continuous engagement with the hammer 44.

The firing pin 46 is biased rearwardly by a captive spring 60 such that a head 62 of the firing pin 46 is exposed in adjacent but spaced relation to the hammer 44 in the neutral or fired position and a tip 64 of the firing pin 46 is normally contained within a recoil plate 66 of the frame 14 in coaxial alignment with the barrel 12.

The trigger 40 pivots about the frame 14 on a pin 68 and is normally maintained in a forward position (FIG. 1) under the bias of a trigger return spring 70. Upon squeezing the trigger 40 rearwardly, a forward nose 72 of the trigger 40 engages a shoulder 74 of the bolt 28 during downward movement thereof to disengage the bolt from its cylinder locking cut 30. Disengagement of the bolt from a locking cut permits the cylinder 16 to be indexed by the hand 42 simultaneously with the pivotal movement of the trigger 40. The hand 42 advances the ratchet ejector 26 at a sufficiently rapid rate such that, upon the trigger nose 72 clearing the shoulder 74 of the bolt 28, the bolt 28 seats within the next locking cut 30 to fix a cylinder chamber in alignment with the barrel 12 before the trigger 40 causes the hammer 44 to be dropped, thereby to ensure against any possibility of actuating the firing pin 46 before a cylinder chamber is fully indexed.

The hammer 44 is thus simultaneously actuated with the trigger 40 and the chamber indexing movements of the cylinder 16. If the cylinder 16 were bound by an unseated bullet, e.g., trigger movement would be interrupted by virtue of the hand 42 being directly mounted for pivotal movement on the trigger 40. A complemen-

tary safety feature is provided by a safety connector 76 which, like the hand 42, is also supported for pivotal movement directly on the trigger 40 to be positioned between the hammer 44 and the firing pin 46. The latter thus is conditioned to be fired only when the trigger 40 is held rearwardly, preferably after moving the hammer 44 into the fully cocked position (FIG. 2).

To position both the hand and connector elements 42, 76, while yet ensuring an improved, simplified construction incorporating a minimum number of parts, a spring 78 is mounted between the hand 42 and connector 76 to continuously urge them respectively toward and away from the cylinder 16. Positive contact engagement between the hand 42 and ratchet ejector 26 is thereby ensured while also preventing any possibility of interference between the connector 76 and the exposed head 62 of the firing pin 46. In the specific illustrated embodiment of this invention, the spring 78 is a generally flat leaf spring shown carried by the connector 76 and suitably configured with a reverse bend. Such construction provides an intermediate spring portion 80 engaging the connector 76 to urge it away from the cylinder 16 while a free end portion 82 of the spring 78 contacts the hand 42 to bias it toward the cylinder 16 into initial contact with a guide pin 84 on the frame 14. Both the hand 42 and connector 76 are continuously urged in such opposite angular directions irrespective of their relative positions throughout the entire movement of the trigger 40.

Both single and double action movements of the firing mechanism 18 are provided for in the revolver 10 of this invention. In a single action movement, the hammer 44 is manually cocked by depressing its hammer spur 86 and then released from the cocked position by a trigger squeeze which remains substantially constant in all of the discrete cylinder positions. In contrast, the hammer 44 is both cocked and released by a single trigger squeeze in a double action movement.

During cocking of the firing mechanism 18, hammer movement is effected in accordance with another feature of the illustrated embodiment by a significantly simplified sear construction. A rear nose portion 88 is provided on the trigger 40 incorporating a novel profile of reduced thickness in the direction of the pivotal axis of the trigger 40 to form a pair of contoured engagement shoulders defining a single action trigger sear portion 90 and a double action trigger sear portion 92. The hammer 44 is formed with a lower finger 94 having a notched end portion defining a single action hammer sear 96. The finger 94 initially engages a shoulder 98 on the rear trigger nose 88 adjacent the single action trigger sear 90 upon depressing the hammer spur 86 to move the trigger 40 rearwardly to engage the single action sear portions 90 and 96 of the trigger 40 and hammer 44, thereby to hold the hammer 44 cocked until it is released by a trigger squeeze causing the single action trigger sear 90 to move upwardly and disengage the single action hammer sear 96 to fire the revolver 10.

As previously mentioned, a revolver designed in accordance with the invention is characterized by a constant trigger squeeze during single action operation. Referring to FIGS. 6 and 7, it can be seen that a small pivotal displacement $\Delta\theta$ of the trigger 40 is necessary to disengage the trigger sear from the single action hammer so that the hammer may fall from the cocked position of FIG. 2 to the fired position of FIG. 1. The trigger

sear displacement is designated d in FIG. 6 and is obviously related to the pivotal displacement $\Delta\theta$ as follows:

$$d = R_1 \Delta\theta \quad (1)$$

wherein: R_1 is the radial distance of the trigger sear from the trigger's pivot 68.

This pivotal displacement $\Delta\theta$ also procures a displacement D of the pin 42a which is expressed by the equation:

$$D = R_2 \Delta\theta \quad (2)$$

wherein: R_2 is the radial distance of the pin 42a from the trigger's pivot 68.

Thus, during single action operation, the pin 42a, upon which the hand is mounted, moves a distance approximately equal to the ratio of the radial distance of the pin 42a from the pivot of the trigger to the radial distance of the trigger sear from the pivot of the trigger times the distance traversed by the trigger sear in clearing the hammer sear.

It has been found that it is virtually impossible to manufacture the ratchet 26 so that the extremity of the hand 42 will encounter the same resistance in all cylinder positions when the trigger is squeezed in single action operation. This is because the timing of the gun is the controlling consideration in machining the ratchet. In a properly timed gun, pulling the trigger in the FIG. 1 position thereof or cocking the hammer accurately positions the cylinder in a discrete position in which the bolt 28 engages a locking cut 30, thereby precisely aligning the selected cylinder chamber with the barrel.

If the extremity of the hand encounters varying resistance from the ratchet in the discrete positions of the cylinder when the trigger is squeezed during single action operation, the necessary trigger force in respective discrete cylinder positions to disengage the trigger sear from the hammer sear will be correspondingly varied. Clearly, if there were no play between the pin 42a and the hand 42, this resistance would be transmitted to the trigger 40.

It will be noted that the hand 42 is loosely mounted on the pin 42a by virtue of the hole 42b being larger than the pin. The hole is sufficiently large so that the pin 42a is substantially linearly movable therein a distance at least approximately equal to $R_2/R_1 d$ and therefore, when the trigger is squeezed during single action operation, this motion is not transmitted to the hand 42 until the trigger sear has cleared the hammer sear.

Alternatively, as shown in FIG. 8, a hand 42' may be provided with a pin structure 42c and the trigger may be provided with a hole (not shown) to receive the pin, the hole, of course, being larger than the pin to loosely mount the hand upon the trigger. This alternative arrangement is the equivalent of that shown in FIGS. 1-7 and will similarly result in a constant trigger pull in the various cylinder positions. It will be understood that in this embodiment of the invention, the movement of the trigger to effect release of the hammer, when it is in a cocked position, will not cause sliding movement of the hand on the ratchet because the periphery of the hole in the trigger will not displace the hand along its axis until the trigger sear has been disengaged from the hammer sear.

Moreover, the hand and trigger could each be provided with a pin structure and the respective pin structures could be loosely joined by a suitable coupling.

In the illustrative revolver, a hammer strut 100 constitutes a double action hammer sear and a positive force is applied along the length of the strut 100 responsive to rearward movement of the trigger 40. Upon squeezing the trigger 40, the double action trigger sear 92 engages the hammer strut 100 to move the hammer 44 into the fully cocked position and, coincidentally with further rearward movement of the trigger 40, the hammer strut 100 rides off the contact surface of the double action trigger sear 92 to drop the hammer 44 to fire a cartridge.

15 It will also be noted that undesired rubbing of the parts is minimized by providing raised pads such as shown at 99 and 101 on the trigger 40 and hammer 44 respectively.

To further minimize the number of working parts 20 while providing additional economies in the manufacture and assembly of the illustrated revolver, the strut 100 is formed with an integral hub bearing portion 102 received for captured pivotal movement within a recess 104 formed in the hammer 44. In addition to minimizing the number of parts normally associated with conventional revolver firing mechanisms, such construction provides further advantages of unitary low cost manufacture and increased stability and strength for dependable service over an extended period of time.

30 To ensure continuous contact engagement between the hammer strut 100 and the cooperating double action trigger sear 92 during rearward movement of the trigger 40 while additionally permitting trigger return to its forwardmost position past the hammer 44 in its fired position, the hammer strut 100 is rearwardly depressible. In this regard, a coil spring 106 continuously urges hammer strut 100 forwardly to an extent limited by engagement between the pivoted strut 100 and the hammer 44.

40 A cylindrical guide 108 receives the coil spring 106 which bottoms against the hammer 44 within a compartment 110 formed therein and against a closed end of the guide 108 to apply continuous spring force against the hammer strut 100 while also permitting it to move rearwardly to allow the trigger 40 to return to the forwardmost position.

In accordance with still another feature of the illustrated revolver for ensuring quick and easy assembly of stocks 112, 114 to the frame 14, a combination sideplate and stock retaining means is provided for releasably securing a sideplate 116 to the frame 14 and for both locating and maintaining the stocks 112, 114 in fixed relation to the frame 14. As best seen in FIG. 3, the combination sideplate and stock retaining means is provided by a fastener 118 removably securing the sideplate 116 to the frame 14 with the fastener 118 comprising a screw 120 and cooperating nut 122 respectively having end portions protruding a discrete distance for receipt in cavities 124 and 126 recessed in an inside wall of the stocks 112 and 114. The cavities 124, 126 are prepositioned and dimensioned to ensure that the screw 120 and nut 122 will intimately engage the stocks 112 and 114 with the stocks overlying corresponding portions of the frame 14 in coextensive alignment. The fastener 118 thus provides multiple functions of not only fastening the sideplate 116 to the frame 14, but also quickly and easily locating the stocks 112, 114 on the frame 14 for attachment, while effec-

tively preventing any undesired angular displacement of the stocks 112, 114 relative to the frame 14 once the stocks are secured thereto by a suitable screw, e.g., not shown.

To maintain the connector 76 against excessive movement away from the cylinder 16 under the force of spring 78, while also ensuring that the hand 42 will be held in operative engagement with ratchet ejector 26 of the cylinder 16 throughout the hammer movement, a recess 128 is formed in an inside wall of the sideplate 116 to provide a shoulder or guide surface 130 for the connector 76. As best seen in FIG. 4, the connector 76 includes a firing pin engagement portion 132 which is offset and disposed laterally outwardly of the recess 128 irrespective of the connector position. As the hammer 44 moves to the cocked position, the connector 76 rides up the shoulder 130, to position its offset portion 132 between the hammer 44 and firing pin 46 while ensuring that the connector 76 will be free of any interference with the firing pin 46 during hammer movement. The spring 78 also maintains the connector 76 in continuous contact engagement with the shoulder 130 to ensure against any possibility of the spring 78 being relaxed to permit disengagement of the hand 42 and the ratchet ejector 26.

A handgun constructed in accordance with this invention not only provides a constant trigger squeeze in single action movements, but also provides for a wider range of manufacturing tolerances due to the loose fit of the hand on the trigger. Also, it will be appreciated that the invention facilitates trigger return, since the hand is jerked downwardly under the bias of the trigger spring.

As will be apparent to persons skilled in the art, various modifications and adaptations of the structure above-described will become readily apparent without departure from the spirit and scope of the invention, as defined by the subjoined claims. For example, the hole 42b and the pin structure 42a need not be cylindrical, but may embody other shapes as long as the hand is loosely mounted. Also, the invention is not limited to pivotally mounted hands and triggers. The trigger could be slideable, if a means to transmit the movement thereof to the hand is provided. If desired, the hand could be mounted in a guide recess in the trigger or in an associated structure. Further, the invention is not limited to revolvers incorporating specially designed hammers or to revolvers incorporating a safety connector as the invention is adapted to be employed in any revolver which utilizes a hand to drive the cylinder ratchet.

I claim:

1. In an improved revolver of the by-pass hand type having a frame, a trigger with a single action sear thereupon movably mounted on the frame, a hammer with a single action sear thereupon pivotally mounted in the frame such that the trigger sear engages the hammer sear when the hammer is in a cocked position, a cylinder mounted for rotation on the frame, a by-pass

ratchet operatively connected to the cylinder and a by-pass hand associated with the trigger for engaging the ratchet and rotating the cylinder, the improvement comprising means to mount the hand for movement with the trigger to prevent the movement of the trigger from causing sliding of the hand on the ratchet during disengagement of the trigger sear from the hammer sear.

2. In an improved revolver of the by-pass hand type having a frame, a trigger device, having a single action sear, movably mounted on the frame, a hammer, having a single action sear, mounted on the frame for movement between a cocked position in which the sears are in engagement and a fired position, a small movement of the trigger device being adapted to release the sears from engagement to fire the revolver, a cylinder mounted for rotation between discrete positions on the frame, a by-pass ratchet operatively connected to the cylinder and a by-pass hand device associated with the trigger device and movable therewith for engaging the ratchet and rotating the cylinder, the improvement comprising a structure operatively interconnecting the trigger device and the hand device, the structure being integral with one of the devices, means to loosely receive the structure within the other of the devices such that the small movement of the trigger does not cause the hand to slide over the ratchet, whereby the force required to effect the small movement will be constant in the discrete cylinder positions.

3. An improved revolver of the by-pass hand type having a frame, a trigger device with a single action sear thereupon pivotally mounted on the frame, a hammer with a single action sear thereupon pivotally mounted on the frame such that the trigger device sear engages the hammer sear to prevent falling of the hammer when the hammer is in a cocked position, a cylinder mounted for rotation on the frame, a by-pass ratchet operatively connected to the cylinder, the ratchet being engagable to rotate the cylinder between the discrete firing positions thereof, and a by-pass hand device operatively connected to the trigger device and normally responsive to movements thereof for engaging the ratchet to rotate the cylinder, the improvement comprising a structure extending between the trigger and hand devices, the structure being integral with one of the devices and being loosely received in a hole in the other of the devices such that relative linear movement between the hole and structure is effected when the trigger sear is disengaged from the hammer sear, the linear movement being at least equal to the ratio of the radial distance of the structure from the pivot of the trigger device to the radial distance of the trigger device sear from the pivot of the trigger device times the distance traversed by the trigger sear in clearing the hammer sear during disengagement therebetween, whereby the hand will not slide upon the ratchet during this disengagement.
